UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed February 8, 1923. Serial No. 617,781.

To all whom it may concern:

Be it known that I, WINFRED T. POWELL, a citizen of the United States, residing at Rochester, in the county of Monroe and State of New York, have invented certain new and useful Improvements in Automatic Telephone Systems, of which the following is a full, clear, concise, and exact description.

This invention relates to telephone systems and more particularly to telephone systems in which automatic switching means establish some portion of a telephone connection.

In former telephone systems it has been proposed to employ relays instead of non-numerical switches in extending calling telephone lines to idle trunks, but such arrangements heretofore have been expensive to install and difficult to maintain in operation because of the great number of relays necessary to complete the various interconnections.

The present invention has for its purpose, the reduction of the number of relays and the simplification of the circuits in which such relays are employed.

The main feature of the present invention resides in the arrangement of telephone lines in groups and sub-groups and the means by which the lines of a sub-group are simultaneously extended to idle trunks on the initiation of a call on one of the lines of the sub-group.

Other features of the invention will appear from the detailed description and appended claims:

The drawings with Figures 1, 2, and 3 arranged in the order named, diagrammatically represent a portion of a telephone system incorporating the present invention. At the left of Fig. 1 there are represented two telephone lines, each provided with a sub-station, which are designated A and B respectively. The right hand portion of Fig. 1 and the portion of Fig. 2 at the left of the heavy dotted line represent a group of ten interconnecting relays individual to a pair of lines A and B. The vertical column of relays shown just at the left of the heavy dotted line in Fig. 2 are associated with the primary group of trunks, one of said relays being provided for each pair of said trunks. At the right of the heavy dotted line in

Fig. 2 and at the left hand portion of Fig. 3, there are represented two groups of relays one of said groups of relays being individual to the even group of secondary trunks while the other of said groups of relays is individual to the odd group of secondary trunks. At the upper right hand corner of Fig. 3 and enclosed within the dotted rectangle there is indicated a numerical or connector switch. The disclosure of this numerical switch has been very much abbreviated, only its impulse relay and its first slow releasing relay being shown. It will be understood, however, that first, second and third selectors as well as the indicated connector switch may be interposed between the secondary trunks and the telephone lines. Below the dotted rectangle there are indicated nine slow releasing relays, each one of these relays is associated with a connector switch circuit in the manner similar to that indicated within the dotted rectangle. Although the exact grouping of the telephone lines and the primary and secondary trunks are not essential to this invention, for purposes of this description it is assumed that the telephone lines of the system are divided into groups of one hundred lines each and the lines of each group are arranged in sub-groups or pairs. Each group of one-hundred lines has for its use twenty primary trunks which are divided into two groups arbitrarily designated odd and even. These twenty primary trunks have access to ten secondary trunks. With such a grouping of the lines and trunks ten switching relays individual to each pair of telephone lines serve to interconnect those lines with their twenty primary trunks. A secondary group of ten relays is provided for each primary trunk and serves to connect this trunk with any one of ten secondary trunks.

Reference is made in the course of this description to numerical switches of the selector and connector type which may be of the structure similar to that disclosed in the patents to Keith Erickson and Erickson #815,321 granted March 13, 1906 and #815,176 also granted March 13, 1906. The circuits of the connector switches referred to may be substantially similar to those disclosed between the dotted lines of the drawing in Powell Patent #1,382,012 June 21, 1921, when modified by adding

another set of contact springs for use in the starter wire arrangement shown at the right of Fig. 3 of the present disclosure. The conductor leading to contact 10 of that patent will be omitted.

With this brief description of the layout of the system it is believed the invention will best be understood by describing the method of establishing a telephone connection from a calling telephone line such as that indicated at A to a called telephone line indicated at C in Fig. 3.

When the subscriber at A removes his receiver from its switch hook, the slow releasing line relay 5 is energized in a circuit traceable from grounded battery, winding of this relay, inner back contact and armature of the cut-off relay 6, over the upper side of the calling line and through the substation A in series, over the lower side of the calling line, armature and back contact of cut-off relay 6 to ground. The line relay 5 thereupon attracts its armatures to extend grounded battery to all of the ten primary selecting relays individual to the pair of lines A and B. Since it is assumed that the first pair of primary trunks indicated in heavy lines in Figures 1, 2, and 3 are idle, low wound relay 7 individual to this pair of trunks is inert, so that a circuit is closed from ground at its inner armature and back contact, conductor 8, lower winding of relay 9, conductor 10, innermost front contact and armature of line relay 5 to ground. Relay 9 is energized in this circuit and extends the talking conductors to the calling line, through the upper armatures and front contacts 11 and 12 of relay 9, and conductors 13 and 14 to ground at the inner armature and back contact of relay 15, and to grounded battery through the outer back contact and armature of relay 15 and winding of relay 16. The line relay 16 is energized in this circuit and at its armatures and front contacts applies grounded battery to all of the ten relays individual to the odd group of secondary trunks. Since it is assumed that the first secondary trunk of this group is idle, the slow releasing relay 17, individual to this trunk and its numerical switch, is in its normal condition. A circuit is therefore closed from ground at the outer armature and back contact of this relay, lower winding of switching relay 18, conductor 19, uppermost armature and contact 20 of relay 16, winding of this relay to grounded battery. The relay 18 is thus operated and connects the calling line through the conductors 13 and 14 of the primary trunk through conductors 21 and 22 of the selected secondary trunk circuit leading to the numerical switch indicated within the dotted rectangle.

Immediately on the seizure of the sec-

ondary trunk, impulse relay 23 is energized over the extended connection, including the conductors of the calling line and primary and secondary trunks in series. With the relay 23 energized, the slow releasing relay 17 is operated in the well known manner and at its inner armature and front contact extends ground over conductor 24, contact 25 and inner armature of relay 18, conductor 26, winding of the cut-off relay 15 associated with the primary trunk and in multiple therewith, over conductor 27, contact 28 and armature of relay 9, left hand winding of the cut-off relay 6 of the calling line to grounded battery. The low wound relay 7 is likewise energized in multiple with the last described circuits from grounded battery, winding of this relay conductor 29, the upper winding, contact 30 and armature of relay 18, contact 25, inner front contact and armature of relay 17 to ground.

With the relay 7 actuated, a holding circuit is closed for the switching relay 9 from grounded battery, right hand winding of the relay 6, upper winding of relay 9, innermost front contact and armature of relay 9, conductors 31, and 32, outer front contact and armature of relay 7 to ground. An energizing circuit for the cut-off relay 76 is closed in multiple with the last described circuit. As soon as the cut-off relays 6 of Fig. 1 and 15 of Fig. 2 are actuated the line relays 5 and 16 are disconnected from the calling line and from the primary trunk respectively.

When the calling line has been extended to the numerical switch shown within the rectangle of Fig. 3 the apparatus is in condition to receive directive impulses from the dial switch at the calling station. The remainder of the connection is thereupon established to the called substation C in the well known manner.

Let it be assumed that while the telephone line at A is calling the telephone line at B initiates a call. The initiation of a call on line A has served to connect the line B to the even trunk associated with the trunk to which line A has been connected. The conductors 33 and 34 of the calling line have thus been connected to the conductors 35 and 36 of the even primary trunk but this extension of the line B to this primary trunk is ineffective until the subscriber at B initiates a call. At that time the conductors 33 and 34 of this line are connected in series by the closure of the hook switch so that the line relay 37 (Fig. 3) associated with the even group of secondary trunks is energized from grounded battery, its winding, inner back contact and armature of cut-off relay 38, conductor 36 of the primary trunk, conductor 33 of the calling line, through the hook switch at station B, conductor 34 of the

calling line, conductor 35 of the primary trunk, outer armature and back contact of cut-off relay 38 to ground. The line relay 37 on energization extends battery potential 5 through its front contacts and armatures to the group of ten secondary switching relays which are therefore in readiness to extend the selected even primary trunk to an idle secondary trunk circuit.

10 Since it has been assumed that the first secondary trunk has been seized in extending the line A to the called line C, the relay 17 is operated so that a circuit is now extended from ground, outer armature and front contact of relay 17, armature and back contact of relay 39, conductor 40, upper winding of relay 41, conductor 42, contacts 43 and outer armature of line relay 37 to a grounded battery. The relay 41 is energized in this circuit and extends the conductors 35 and 36 of the even primary trunk through contacts 44 and 45 of relay 41 to a secondary trunk which is not shown but which is similar to the secondary trunk leading to the dotted rectangle of Fig. 3. The seizure of this secondary trunk is effective to actuate the slow releasing relay 39 in the manner similar to the operation of the slow releasing relay 17. The energization 30 of relay 39 extends ground through the armature and front contacts of relays 17 and 39 to the armature and back contact of relay 46 so that the secondary trunk with which this relay is associated is rendered selectable. Also the operation of relay 39 is effective to hold the relay 41 operated and is effective to actuate the cut-off relay 38 which in turn disconnects the line relay 37 from its primary trunk. Also the operation of relay 39 extends the holding ground through the outer armature and front contact 47 of relay 41, lower winding of this relay, connector 48, conductor 29, winding of low resistance relay 7 to grounded battery.

45 The switching relay 41 is thus held operated and this multiple energizing path for the relay 7 maintains the relay 7 operated even after the connection between the line A and C has been disestablished. With the relay 7 thus held operated the switching relay 9 maintains the line B connected to its selected even primary trunk and this connection is maintained irrespective of whether the connection between the lines A and C is released.

50 At the termination of the conversation between A and C, the subscriber at A replaces his receiver on its switch hook, whereupon the impulse relay 23 deenergizes and shortly afterwards the slow-releasing relay 17 retracts its armatures to open the holding circuits for relays 18 and 15 which deenergize and if the line B is not calling over a primary trunk, relay 7, switching relay 9 and cut-off relay 6 are likewise deenergized to

restore the apparatus in condition to complete a succeeding call.

It will be noted that as soon as a calling line such as A has been extended to a secondary trunk ground potential is extended 70 over a conductor such as 27 to the multiple terminals such as 50 of the group of connectors by which this calling line may be reached. This ground potential serves to guard the calling line against intrusion 75 when it is in use.

What is claimed is:—

1. In an automatic telephone system, a plurality of telephone lines arranged in groups and sub-groups, a group of primary 80 trunks arranged in sub-groups, a group of secondary trunks, a relay for connecting each sub-group of telephone lines to a sub-group of primary trunks on the initiation of a telephone call over one of said lines of the 85 sub-group, and automatically controlled means for separately extending the selected primary trunks to secondary trunks.

2. In a telephone system, a plurality of telephone lines arranged in groups and sub-groups, one line relay for each sub-group of telephone lines, a group of primary trunks arranged in sub-groups, secondary trunks, a relay for connecting each sub-group of telephone lines to a sub-group of primary trunks 90 on the initiation of a telephone call over one of said lines of the sub-group, said relay being controlled by said line relay, and means for separately extending the selected primary trunks to secondary trunks. 95

3. In an automatic telephone system, a plurality of telephone lines arranged in groups and pairs, a group of primary trunks arranged in pairs, a group of secondary trunks, a relay for simultaneously extending 100 a pair of telephone lines to a pair of primary trunks and automatically controlled means for separately extending the selected pair of trunks to secondary trunks.

4. In an automatic telephone system, a group of telephone lines arranged in pairs, a group of primary trunks also arranged in pairs, a single switching relay actuated on the initiation of a call over either of the telephone lines of a pair to simultaneously extend 110 said pair of telephone lines to a pair of primary trunks, means for extending the primary trunk to which the calling line is connected, means for extending the other primary trunk of the pair, and means for maintaining said switching relay operated over either of said pair of primary trunks. 115

5. In an automatic telephone system, a plurality of telephone lines arranged in groups and sub-groups, a group of primary 125 trunks arranged in sub-groups, a group of secondary trunks, a relay for connecting each sub-group of telephone lines to a sub-group of primary trunks on the initiation of a telephone call over one of said lines of 130

the sub-group, and automatically controlled relay switching means for separately extending the selected primary trunks to secondary trunks.

- 5 6. In a telephone system, a plurality of telephone lines arranged in groups and sub-groups, one line relay for each sub-group of telephone lines, a group of primary trunks arranged in sub-groups, a relay for connecting each sub-group of telephone lines to a sub-group of primary trunks on the initiation of a telephone call over one of said lines of the sub-group, said relay being controlled by said line relay, and relay switching means for separately extending the selected primary trunks to secondary trunks.
- 10 7. In an automatic telephone system, a plurality of telephone lines arranged in groups and sub-groups, a group of primary trunks arranged in sub-groups, means for allotting primary trunks for use; a group of secondary trunks, a relay for connecting a sub-group of telephone lines to a sub-group of allotted primary trunks on the initiation of a telephone call over one of said telephone lines of the sub-group; and automatically controlled means for separately extending the selected primary trunks to secondary trunks.
- 15 8. In an automatic telephone system, a plurality of telephone lines, arranged in groups and sub-groups, a group of primary trunks arranged in sub-groups; means for allotting primary trunks for use, a group of secondary trunks, means for allotting secondary trunks for use, a relay for connecting a sub-group of telephone lines to a sub-group of allotted primary trunks on the initiation of a telephone call over one of

said telephone lines of the sub-group, and automatically controlled means for separately extending the selected primary trunks to allotted secondary trunks.

9. In an automatic telephone system, a plurality of telephone lines arranged in pairs, a single line relay for each pair of telephone lines, a cut-off relay for each telephone line for disconnecting said telephone line from its associated line relay, pairs of primary trunks, a relay controlled by the line relay of a pair of telephone lines for connecting said lines to a pair of primary trunks, means responsive to said connection for operating the cut-off relays of said pair of telephone lines, and means for separately extending the primary trunks to secondary trunks.

10. In an automatic telephone system, a plurality of telephone lines arranged in pairs, a single line relay for each pair of telephone lines, a cut-off relay for each telephone line for disconnecting said telephone line from its associated line relay, pairs of primary trunks, a relay controlled by the line relay of a pair of telephone lines for connecting said lines to a pair of primary trunks, means responsive to said connection for operating the cut-off relays of said pair of telephone lines, said means including a circuit extending through windings of said relay and said cut-off relays, and means for separately extending the selected primary trunks to secondary trunks.

In witness whereof, I hereunto subscribe my name this 5th day of February A. D. 1923.

WINFRED T. POWELL.
